UNITED STATES PATENT OFFICE

LORA E. POOLE, OF ANDERSON, INDIANA, ASSIGNOR TO DELCO-REMY CORPORATION, OF ANDERSON, INDIANA, A CORPORATION OF DELAWARE

METAL BENDING APPARATUS

Application filed September 16, 1929. Serial No. 392,925.

This invention relates to metal bending apparatus and more especially to apparatus for bending a metal strip, such as an electrical conductor, and for cutting the strip at a certain distance from the portion which is bent.

One of the objects of the present invention is to provide apparatus whereby the bending and cutting of metal strips may be performed more economically than heretofore. In order to accomplish this object the present invention comprises a stationary form including a cylindrical portion about which a metal strip may be bent, means for maintaining the strip against the form during the bending operation, an oscillatable support rotating about the axis of the cylindrical portion of the stationary form, means carried by the support for causing the strip to be bent about said cylindrical portion, a movable cutter carried about said support for severing the strip at a predetermined location relative to its bent portion, and means for rotating the support.

Further objects and advantages of the present invention will be apparent from the following description, reference being had to the accompanying drawings wherein a preferred embodiment of one form of the present invention is clearly shown.

In the drawings:

Figs. 1, 2, and 3 are fragmentary diagrammatic plan views of apparatus embodying the present invention showing different stages of operation.

Fig. 4 is a plan view of the apparatus drawn on a larger scale than the preceding views.

Fig. 5 is a sectional view on line 5—5 of Fig. 4.

Figs. 6, 7, and 8 are sectional views taken respectively on line 6—6, 7—7, 8—8 of Fig. 5.

Fig. 9 is a sectional view on line 9—9 of Fig. 4.

Referring to Figs. 1, 2, and 3 numeral 20 in Fig. 1 refers to any strip of metal such as, for example, a lead wire of an electrical coil 21 which is placed around a supporting block 22 attached by a screw 23 to the platform 24 of a frame and gear housing member 25. The block 22 is located by dowels 26. Numeral

27 designates a stationary form block having a cylindrical surface 28 about which the wire 20 is bent progressively into positions 20a and 20b shown respectively in Figs. 2 and 3. The form block is secured by means not shown to a block 29, and both blocks are secured to the platform 24 by screws 30 and are located by dowels 31.

The wire 20 is maintained in engagement with the form during the bending operation partly by reason of the fact that this wire extends from the coil 21 which is maintained in fixed relation relative to the block 27, and partly by reason of the fact that the wire 20 is engaged by finger 32 extending from a block 33 secured to the platform 24 by a screw 34 and located by dowels 35.

The wire 20 is formed about the cylindrical surface 28 of the stationary block 27 by a movable forming block 40 which is mounted eccentrically upon an oscillatable support or shaft 41 which rotates about the axis of the cylindrical portion 28. The block 40 has a surface 42 which is adapted to engage the wire 20 and to cause it to move into the position shown in 20a of Fig. 2. The block 40 has a cutting edge 43 which cooperates with a stationary cutter 44 to cut the wire 20 at a certain location relative to its bent portion. The cutter 44 is adjustably received by a suitable groove in the block 29 and is secured in the desired position relative to the block 40 by screws 45. After that portion of the wire 20 located to the left of the cutting edge 43 has been severed, the remaining portion of the wire is bent into the position 20b as the result of further counterclockwise movement of the block 40. This completes the operation of the present machine upon the wire 20; and the block 40 is returned by means to be described to the position shown in Fig. 1.

The present invention provides power operated means for rotating the shaft 41 in a counterclockwise direction as viewed in Figs. 1 to 4 in order to perform the bending and cutting operations, and a spring for returning the shaft 41 to normal position after these operations have been performed. Referring to Figs. 4 to 9 numeral 50 designates a power shaft driven by any suitable means

not shown and driving a worm 51 which meshes with a worm gear 52 attached in any suitable manner not shown to a disk 53 having a hub 54 attached to a shaft 55 journalled in bearings 56 and 57 located respectively in the platform 24 of frame 25 and in a cylindrical boss 58 integral with a base 59. The disk 53 is provided with an annular row of clutch teeth 60 which are adapted to engage clutch teeth 61 arranged in an annular row upon the upper end face of a mutilated gear 62 which is loosely rotatable about the shaft 55. Normally the clutch teeth 61 are separated from the clutch teeth 60. The gear 62 is urged away from the disk 53 and into contact with the disk 63 fixed to the boss 58 by springs 64 which are located in spring recesses 65 in the hub 54 of disk 53 and which urge plungers 66 against the upper end face 20 of gear 62. The gear 62 is provided with a segmental locating lug 70 which is normally received by segmental notch 71 in the block 63.

The gear 62 meshes with a mutilated gear 80 attached to the shaft 41. The gear 80 is normally maintained in the position shown in Figs. 4 and 7 by a spiral spring 81 having one end attached to a stud 82 and the other to the shaft 41, the spring being constructed and arranged for urging the shaft 41 in a clockwise direction. Motion of the shaft 41 in this direction is limited by reason of the fact that the gear 80 carries a stop lug 83 which engages the inner end of a stop screw 84 which is threaded through a side wall of the housing 25 and which is fixed in the desired position of adjustment by a lock nut 85. The gear 62 is normally maintained in the position shown in Figs. 4 and 7 since the lug 70 is normally received by the notch 71. In this way, the end tooth 80a of gear 80 is normally located in the annular space between end teeth 62a and 62b of gear 62, and gear 80 is normally located in the path of movement 45 of the gear teeth of gear 62. Hence clockwise rotation of gear 62 will first cause gear 80 to make a one half turn in a counterclockwise direction in order to move the form block 40 from the position shown in Fig. 1 to that shown in Fig. 3. Following this the gear 80 will be free of the gear 62 so that the spring 81 will be operative to return the block 40 to normal position by effecting clockwise rotation of the shaft 41.

55 The connection of the gear 62 with the gear 52 is controlled by a suitable pedal not shown but operatively connected by a suitable means with a lever 90 pivoted at 91 upon the base 59 and pivotally connected at 92 with a plunger 93 extending through the boss 58 and the plate 63 and urged downwardly by a spring 94. To start the machine into operation, the operator causes the lever 90 to be moved in a clockwise direction as viewed in Fig. 5 thereby causing the gear 62 to be raised until the

lower surface of the lug 70 is above the plate 63 thereby causing the clutch teeth 61 to be engaged by the clutch teeth 60. This will cause the gear 62 to be rotated in a direction of arrow 100 in Fig. 5 and the lug 70 to be moved 70 out of registration with the notch 71. Then the lever 90 may be released. The gear 62 will continue to rotate as indicated and cause the gear 80 to make a one half turn in the direction indicated by arrow 101 in Fig. 5 75 for the purpose of rotating the shaft 41 as has been explained. At the end of one revolution of gear 62 its locating lug 70 will register again with the notch 71 thereby permitting the gear 62 to be lowered due to the action of the spring urged plungers 66 which tend to force the gear 62 downwardly thereby separating the clutch teeth 61 from the teeth 60. In this way, the machine is brought to rest automatically at the end of one cycle of 85 its operation.

While the form of embodiment of the present invention as herein disclosed, constitutes a preferred form, it is to be understood that other forms might be adopted, all coming 90 within the scope of the claims which follow.

What is claimed is as follows:

1. Metal bending and cutting apparatus comprising, in combination, a stationary bending form, means for maintaining a metal 95 strip against the form, and a single means for bending the strip about the form and for severing the strip at a predetermined location relative to its bent portion, after part of the bending operation is completed. 100

2. Metal bending and cutting apparatus comprising, in combination, a stationary form including a cylindrical portion about which a metal strip may be bent, means for maintaining a metal strip against the form, an oscillatable support rotating about the axis of the cylindrical portion of the stationary form, a block carried by the support eccentric to its axis and having a surface for engaging the strip to cause the strip to be 110 bent around the form, said block having a shearing edge defining a termination of said strip engaging surface, a stationary shear block cooperating with said shearing edge, 115 and means for rotating the support.

3. Metal bending apparatus comprising, in combination, a stationary bending form, having a cylindrical portion, means for maintaining a metal strip against the form, an oscillatable support rotating about the axis of the cylindrical portion of the stationary form, a forming block carried by said support eccentric to said axis and having a surface adapted to engage the strip and cause it to be 125 bent around said cylindrical portion, a power shaft, a train of mutilated gears for transmitting motion from the power shaft to the rotatable support in one direction to cause the block to bend the strip, and a spring for re- 130

turning the rotatable support to normal position.

4. Metal bending apparatus comprising, in combination, a stationary bending form, having a cylindrical portion, means for maintaining a metal strip against the form, an oscillatable support rotating about the axis of the cylindrical portion of the stationary form, a forming block carried by said support eccentric to said axis and having a surface adapted to engage the strip and cause it to be bent around said cylindrical portion, a power shaft, a train of mutilated gears for transmitting motion from the power shaft to the rotatable support in one direction to cause the block to bend the strip, and a clutch for connecting the power shaft with the mutilated gear train, means for causing the clutch to be engaged, a spring for returning the rotatable support to normal position, and means for automatically causing the clutch to be disengaged at the end of one cycle of operation of the apparatus.

5. Metal bending and cutting apparatus comprising in combination, a stationary form having a cylindrical surface about which a metal strip may be bent, means for maintaining a metal strip against the form, a member adapted to oscillate around the axis of the cylindrical surface of said stationary form, means carried by said member for bending the strip around said cylindrical surface and for severing the strip at a predetermined location relative to the bent portion subsequent to part of the bending operation.

6. Metal bending and cutting apparatus comprising in combination, a stationary form having a cylindrical surface about which a metal strip may be bent, means for maintaining a metal strip against the form, a member adapted to oscillate around the axis of the cylindrical surface of said stationary form, means carried by said member for bending the strip around said cylindrical surface, means cooperating with the bending means for severing the strip at a predetermined position relative to its bent portion, and means for oscillating said member.

7. Metal bending and cutting apparatus comprising in combination, a stationary form having a cylindrical surface about which a metal strip may be bent, means for maintaining a metal strip against the form, a member adapted to oscillate around the axis of the cylindrical surface of said stationary form, and to bend the strip around said cylindrical surface, cutting means including a movable cutter carried by said oscillatable member for severing the strip at a predetermined location relative to its bent portion after part of the bending operation is completed and means for oscillating said member.

8. Metal bending and cutting apparatus comprising in combination, a stationary form

having a cylindrical surface about which a metal strip may be bent, means for maintaining a metal strip against the form, a member adapted to oscillate around the axis of the cylindrical surface of said stationary form, means carried by said member for bending the strip around said cylindrical surface, said bending means forming a movable cutter element, a stationary cutter adapted to cooperate with said movable cutter for severing the strip at a predetermined location relative to its bent portion and means for oscillating said member.

In testimony whereof I hereto affix my signature.
